UNITED STATES PATENT OFFICE.

LOUIS B. NEWELL, OF BALTIMORE, MARYLAND.

METHOD OF ORNAMENTING GLASS ARTICLES.

Application filed December 16, 1921. Serial No. 522,918.

To all whom it may concern:

Be it known that I, LOUIS B. NEWELL, a citizen of the United States, residing at Baltimore, Maryland, have invented a new 5 and useful Method of Ornamenting Glass Articles, of which the following is a specification.

This invention relates to a method of 10 ornamenting glass articles such as bottles and other containers, one of the objects of the invention being to provide a bottle having a translucent surface on which is produced a transparent design, the formation of the contrasting translucent and 15 transparent surfaces being produced in an inexpensive and rapid manner with the result that the transparent design stands out prominently whether viewed direct or through the back of the bottle.

20 With the foregoing and other objects in view which will appear as the description proceeds, the invention resides in certain novel steps in the method hereinafter described and claimed, it being understood 25 that, within the scope of what is claimed, changes in the precise embodiment of the invention shown can be made without departing from the spirit of the invention.

In the accompanying drawings one form 30 of bottle produced by the method constituting the invention has been shown.

In said drawings—

Figure 1 is a view of a bottle showing 35 the design after the first step of the method has been completed.

Figure 2 is a view showing the bottle after the completion of the ornamentation thereof.

40 Referring to the figures by characters of reference 1 designates a bottle or other glass container adapted to be blown within a mold whereby a raised design will be

produced on the outer surface of one or more walls of the bottle, this design being indicated at 2. The surfaces of the bottle 45 on which the design is molded are then frosted by means of a sand blast or the like after which the bottle or other container will have the frosted or translucent appearance illustrated in Figure 1. On the 50 completion of this frosting operation the ornamental surface is placed in contact with a buffing element which will contact solely with the raised portions of the surface with the result that these raised portions will be 55 polished and will stand out with increased prominence upon the frosted surface and will be transparent. Consequently when the bottle is filled with a colored liquid these transparent lines of the design will stand 60 out with even greater prominence than when the bottle is empty but under all conditions the design will have the appearance 65 of being etched on the bottle and a container having a high grade appearance can 70 thus be produced in a very inexpensive manner.

What is claimed is:—

The herein described method of ornamenting glass articles which consists in forming 70 on a surface of the article projecting portions forming a design, subsequently frosting both the raised and sunken portions of said surface at one operation, and finally buffing the projecting portions of the surface to render the design transparent and leave a frosted background.

75 In testimony that I claim the foregoing as my own, I have hereto affixed my signature in the presence of two witnesses.

LOUIS B. NEWELL.

Witnesses:

WALTER R. LEACH,
JAS. G. B. MOORE.
